UNITED STATES PATENT OFFICE.

KURT H. STUBENVOLL, OF EAU CLAIRE, WISCONSIN, ASSIGNOR TO GILLETTE RUBBER CO., OF EAU CLAIRE, WISCONSIN, A CORPORATION OF MAINE.

DESIGN FOR A TIRE-CASING OR A SIMILAR ARTICLE.

54,290.

Specification for Design.

Patented Dec. 9, 1919.

Application filed March 19, 1919. Serial No. 283,679. Term of patent 14 years.

To all whom it may concern:

Be it known that I, KURT HUGO STUBENVOLL, a citizen of the United States, and residing in the city of Eau Claire, county of Eau Claire, and State of Wisconsin, have invented a new, original, and ornamental Design for a Tire-Casing or Similar Articles, of which the following is the specification, reference being had to the accompanying drawings, forming a part thereof.

In the drawings:

Figure 1 is a fragmentary top plan view

of a tire casing illustrating the design embodying my invention;

Fig. 2 is a transverse section thereof.

I claim:

The ornamental design for a tire casing or similar article, as shown.

KURT H. STUBENVOLL.
